UNITED STATES PATENT OFFICE.

STEPHEN TOTH, OF FURNACE RUN, PENNSYLVANIA.

WEAPON.

1,188,511.

Specification of Letters Patent. Patented June 27, 1916.

Application filed May 11, 1916. Serial No. 96,783.

To all whom it may concern:

Be it known that I, STEPHEN TOTH, a subject of the King of Hungary, residing at Furnace Run, in the county of Armstrong and State of Pennsylvania, have invented 5 certain new and useful Improvements in Weapons, of which the following is a specification.

The primary object of the invention is the 0 provision of a weapon in the nature of a combined firearm and sword, the firearm being readily locked against operation when designed for employment as a sword.

A further object of the device is the 5 provision of a revolver having a bayonet or sword operatively secured thereto, a common handle being employed for both the sword and revolver.

The present invention contemplates the 0 rigid mounting of a blade in advance of the barrel of a revolver whereby the same may be employed as a sword or bayonet simultaneously with the shooting thereof, a protected or guarded handle being arranged for 5 the weapon.

With these general objects in view and others that will appear as the nature of the invention is better understood, the same consists in the novel construction, combination 0 and arrangement of parts hereinafter more fully described, illustrated in the accompanying drawings, and then claimed.

In the drawings forming a part of this application and in which like designating 5 characters refer to corresponding parts throughout the several views:—Figure 1 is a side elevation of the device. Fig. 2 is a top plan view thereof, and Fig. 3 is a transverse sectional view taken upon line 0 III—III of Fig. 1.

Broadly considered, the present invention resides in a unitary weapon in the form of a revolver 10 having a bayonet blade or sword 11 rigidly secured to the tubular barrel 12 5 thereof while the magazine 13 of the revolver may be locked against turning by means of a latch 14, and a hand guard 15 of strap formation is carried by the revolver handle 16.

0 The sword blade 11 is provided with a slightly enlarged off-set base portion 17 arranged with a side plate 18 secured thereto by means of bolts 19 and rivets 20, the said base and plate having coöperating receiving 5 grooves 21 for inclosing the barrel 12.

Two of the bolts 19 are adapted to be secured through the top rib 22 of the barrel while one of the said bolts is secured through the lower rib 23 thereof, thus firmly securing the blade base 17 to the barrel 12, the blade 60 extending in advance of the forward free end of the barrel.

The aforementioned latch 14 is pivoted as at 24 to the revolver 10 and is provided with an angular locking end 25 adapted to be 65 seated within any one of the longitudinal edge grooves 26 of the chamber 13 whenever desired to hold the latter against turning, thus preventing a pulling of the trigger 27 and the firing of the revolver.

The strap guard 15 is secured at one end to the butt of the revolver handle 16 centrally thereof as at 28 and passing in the form of a loop toward the chamber 13, the same is secured at its opposite end to the side 75 face of the revolver as at 29, thus forming a guard over the hand of the operator when grasping the handle 16 in the employment of the weapon.

It will thus be apparent that any form of 80 revolver or pistol may be readily supplied with a sword blade 11 by means of the aforementioned bolts and rivets and that upon grasping the handle 16 of the revolver, the latter may be employed for shooting, or the 85 chamber 13 may be locked by means of the latch 14 when desired and the device employed solely as a sword or cutting weapon.

While the form of the invention herein shown and described is what is believed to 90 be the preferred embodiment thereof, it is nevertheless to be understood that various forms, modifications and arrangements of the parts may be made without departing from the spirit and scope of the invention as 95 claimed.

What I claim as new is:—

1. A weapon comprising a revolver, a hand guard of strap formation secured adjacent the handle portion thereof, a locking latch for the cartridge chamber of the revolver, and a cutting blade provided with a base portion rigidly secured to the barrel of the revolver and extending in advance of the free end thereof. 100

2. A weapon comprising in combination with a revolver having a barrel provided with oppositely arranged upper and lower longitudinal webs, a sword blade having an off-set base portion, a side plate removably 110

secured to the said base portion and conforming to the shape thereof, the said base portion and side plate having coöperating inner faces in engagement with the said barrel and webs, and removable securing means positioned through the said webs, base portion and side plates, with the said barrel

and webs in inclosed relations between the base portion and side plate when operatively positioned with the said blade extending in advance of the said barrel.

In testimony whereof I affix my signature.

STEPHEN TOTH.
